UNITED STATES PATENT OFFICE.

FREDERICK W. KIDDIE, OF LEAMINGTON, ENGLAND, ASSIGNOR TO WINGET LIMITED, OF LONDON, ENGLAND.

MACHINE FOR MIXING CONCRETE INGREDIENTS OR OTHER SUBSTANCES.

1,419,737.

Specification of Letters Patent. Patented June 13, 1922.

Application filed May 27, 1919. Serial No. 300,140.

To all whom it may concern:

Be it known that I, FREDERICK WEBSTER KIDDIE, citizen of Great Britain, residing at 26 Binswood Avenue, Leamington, in the county of Warwick, England, have invented certain new and useful Improvements Relating to Machines for Mixing Concrete Ingredients or Other Substances, of which the following is a specification.

10 This invention relates to machines for mixing concrete ingredients or other substances, and its objects are to improve the quality of the mixture, reduce the time required for its completion, and furthermore 15 attain both these aims with a smaller expenditure of power. My invention therefore has marked advantages both as regards the process and the product.

In order to explain my invention clearly, 20 I will refer hereinafter to the accompanying drawings illustrating my invention, in which,

Figure 1 is a side elevation of the complete machine.

25 Figure 2 is a view of one end, and Figure 3 the other end (the engine or motor being omitted).

Figure 4 is an end view showing the movable part of the machine in tilted position 30 (the gear casing being removed).

Figure 5 is a vertical section (on a larger scale) taken longitudinally through the bearing at one end of the machine.

Figure 6 is a section at right angles to Fig. 35 5, certain parts being omitted.

Figure 7 is a front elevation of the end bearing.

Figures 8 and 9 are a front and side elevation respectively of one of the mixing 40 shovels.

The same numerals repeated in the different figures denote the same or corresponding parts of the machine.

The machine is of the kind which comprises 45 a semi-cylindrical trough 4, placed horizontally, and containing an axial shaft 5 on which beaters are mounted for stirring the contents of the trough when the shaft 5 is rotated.

50 Briefly describing my present improvements, the beaters (sometimes called ploughs or shovels) are each in the form of a shank 1 bearing a two pronged fork 3, and chains 2 stretched not too tightly between the 55 prongs 3. There may be, for instance, three

of such chains 2 arranged parallel and designed after any convenient pattern. The furthest of such chains sags slightly, as shown, and will scrape a definite path along the curved interior of the trough 4. The beaters or ploughs 1, 3, which are mounted radially at intervals along the shaft, will collectively scrape the whole of the internal cylindrical surface at each revolution.

The shape and position of the fork 3, 3, 65 and its shank 1 has an important relation to its effectiveness. This can be best explained by referring to Figure 9 and regarding the beater 1, 3 for the sake of illustration, as a shovel, the blade 3, 3, of which is 70 bent at an angle with its shank 1. The shank 1 is twisted slightly so as to set the edge of the blade (or tips of prongs 3) out of parallel with the shaft 5 (Figs. 1 and 5), and it is also bent back (Fig. 9) in such manner 75 as to bring the centre of such edge (or point between the tips of prongs 3, 3) in radial line with the shank 1. In this way, the necessary sweeping action of the beaters or shovels 1, 3 is obtained. The outer portion 80 of each end fork of the series may be fitted with a chain 6 (Fig. 5) extending to the shaft 5 for sweeping the flat ends of the trough 4.

The trough 4 is capable of being tilted 85 axially for emptying contents, for which purpose, a toothed segment 7 (Fig. 4) is mounted on a hollow trunnion pin 8 secured to the end of the trough by bolts 9 (Figs. 6 and 7). The pin 8, being hollow, 90 serves as a bearing for one end of the shaft 5. The trunnion pin 8 is supported in a bearing 10. The segment 7 is engaged by another toothed segment 11 hinged upon a pin 13, and carrying a hand lever 12. 95

The shaft 5 may be worked by the shaft 17 of an oil engine or other motor (the fly wheels 14 of which only are shown in Fig. 1) mounted upon the carriage frame 15, which carries the whole machine. The frame 100 15 is provided with wheels 16 for moving the whole from one place to another. The coupling between the shaft 5 and the motor-shaft 17, may have slight play in all directions. 105

As illustrated in Figure 1, this coupling comprises a loose disc 18 grooved or ribbed upon both sides, the direction of the grooving or ribbing upon one side being at right angles to that on the other. For instance, 110

one side of the disc 18 may have a groove *a*, and the other side a rib *b*, or if preferred, *a* and *b* may both be ribs or both grooves, the disc 18 being situated between the driven member 5 and the driving member 17, both of which are similarly grooved and ribbed. In this manner, sliding play can be obtained without impairing the positive driving effect. This is a distinct advantage, owing to 10 the unavoidable resiliency of the frame 15.

The trough 4 is surmounted by a hopper 19 (Figs. 1 and 2) furnished at the bottom with a slideable door 20, worked by a lever 21. A water tank 22 may be provided with 15 spraying pipe 23 of any suitable kind for wetting the ingredients in the trough 4 either before or during the mixing operation.

The trunnion bearing 10 (Figs. 1 and 4) 20 is carried on a standard or upright frame 24 mounted upon the carriage frame 15, and there is another frame or standard 24^a (Figs. 1 and 3) at the opposite end of the machine to carry the other trunnion member. A stationary delivery chute 25 may be fitted to 25 the frame to receive and direct the material which becomes tipped out of the trough 4 when the latter is swung by means of the hand lever 12 into the position shown in 30 Figure 4.

The segmental tilting gear 7, 11 is protected by a casing 26 (Figs. 1 and 2), which is slotted to enable the hand lever 12 to project therethrough, such lever being stepped 35 or crank-shaped for this purpose.

The machine with the motor forms a self-contained unit, which can be readily wheeled or conveyed to the place where the work of mixing is to be done.

40 I claim:—

1. For use in machines for mixing concrete ingredients or other substances, beaters mounted upon a shaft, each beater consisting of a single shank carrying a fork, and 45 having chain form connecting means between the prongs of same, the said shanks being inclined out of the radial lines, in order that the forks and chain form connecting means work the concrete endwise of the trough and 50 more perfectly mix the concrete.

2. For use in a machine of the kind specified, a beater having a shank inclined from the radial line and carrying a fork provided with a chain form connecting means extending 55 from prong to prong thereof, in which beater the prongs are bent at such an angle with the single shank that their tips are practically in the radial line of the same.

3. For the use above specified, a beater 60 consisting of a shank and fork provided with a chain form connecting means from prong to prong and so directed and arranged as to mix the concrete when carried around in revolution, said beater being combined with a 65 shaft and so mounted on the same that the

line between the tips of the prongs is out of parallel with such shaft, thus leaving only one point of such line within the radial line of the shank, and so producing the desired sweeping effect in the trough of the machine 70 as the shaft rotates.

4. For the use above specified, a plurality of beaters or ploughs, mounted in a trough at suitable distances apart upon a common rotary shaft, with a scraping device extending 75 from the shaft (at each end) to the terminal prong for the purpose of sweeping also the ends of said trough.

5. In concrete mixers, the combination of a rotary shaft having a bore extending from 80 face to face through said shaft and at right angles to the axis thereof and a receptacle in which said shaft rotates, with a beater consisting of a fastening stem extending through said bore, a shoulder at the base of 85 said stem engaging the face of the adjacent portion of said shaft, a shank extending from said shoulder at an angle to said stem so as to extend, in any position of adjustment, appreciably to one side of the radial 90 line passing through the center of said bore, and a fork carried by the radially outer end of said shank and so formed that the central point of a line drawn from the tips of its prongs will be intersected by a radial line 95 passing through the center of said bore, and flexible means extending between, and connected to, the prongs of said fork to operate upon the plastic mass with a sweeping action impelling the mass longitudinally, radially and peripherally, and means working 100 on said stem for securing the same in said bore.

6. A beater to be mounted on the shaft of a rotary concrete mixer consisting of a stem 105 to be passed through said shaft, a shoulder at the base of said stem, a shank extending from said shoulder at an abrupt angle to said stem, a fork extending from said shank and presented at a reverse angle thereto toward a line coincident with the longitudinal central line of said stem, and a flexible element extending from prong to prong of said fork and connected to said prongs.

7. In a concrete mixer, a trough, a shaft 115 mounted to act upon material in said trough, and means for rotating said shaft, in combination with two series of beaters mounted to turn with said shaft, each beater of one series having an operative portion provided 120 with a flexible element, said portion extending longitudinally of the shaft, but at an angle thereto to give a longitudinal impulse, and lying as a whole in a plane at an inclination to every radial plane to give a radial impulse, the operative portion of each beater of said series lying parallel to the operative portions of the other beaters of said series, and each beater of the other series having a similar operative portion extend- 125 130

ing longitudinally of the shaft, but at an angle thereto reverse to the angle of the first series, and lying as a whole in a plane at an inclination to every radial plane to give a 5 radial impulse, the operative portion of each beater of said second series lying parallel to the operative portions of the other beaters of said series.

In testimony whereof, I have signed my name to this specification in the presence of 10 two subscribing witnesses.

FREDERICK W. KIDDIE.
